ELECTRIC LANTERN

Filed April 23, 1928

UNITED STATES PATENT OFFICE

WILLIAM E. JACKSON, OF AMARILLO, TEXAS

ELECTRIC LANTERN

Application filed April 23, 1928. Serial No. 272,302.

The present invention relates to lanterns, and the primary object of the invention is to provide an improved electric hand lantern which while being especially well adapted for use by car inspectors, repairmen, car checkers and the like, will be found susceptible of general use where a portable light is found desirable.

A further object of the invention is to provide an electric hand lantern embodying novel features of construction whereby replacements may be readily and easily made.

A further object of the invention is to provide an electric hand lantern having a casing or housing of novel construction for enclosing the battery and lamp, and a frame of novel construction embodying hand gripping portions allowing for ready and easy handling of the lantern and a stand whereby the lantern may be rested upon a surface in its upright position.

A further object of the invention is to provide an electric hand lantern embodying a novel circuit controlling means which will be efficient in operation and of such construction as to permit of the housing being constructed of any desired material and not necessarily of metal to form a conductor between the battery and lamp.

Other objects and advantages of the invention will be apparent during the course of the following detailed description, taken in connection with the accompanying drawing, forming a part of this specification and in which drawing:

Figure 1 is a side elevation of the improved lantern.

Figure 2 is a transverse section taken substantially on the line 2-2 of Figure 3 and looking in the direction of the arrows.

Figure 3 is a central longitudinal section thru the casing or housing for receiving the storage battery cell, and in which housing the lamp is mounted.

Figure 4 is a transverse section on line 4-4 of Figure 3 and looking in the direction of the arrows.

Figure 5 is a fragmentary longitudinal section illustrating the construction of the switch operating means for manually con-

trolling the circuit to the electric lamp.

Figure 6 is a face plan view of the front contact ring before mounting on the insulating disc.

Figure 7 is a plan view of the front contact disc with which one terminal of the electric lamp contacts.

Figure 8 is a fragmentary face plan view of the switch arm to be actuated by the switch operating means for controlling the circuit to the electric lamp.

Referring to the drawing in detail, and wherein similar reference characters designate corresponding parts thruout the several views, the improved electric hand lantern has been shown as embodying a cylindrical shaped casing or housing A and a supporting frame or stand B for allowing ready and easy handling of the casing A.

Referring first to the specific and novel construction of the casing or housing A, the same embodies a tubular body portion 10 being open at both ends as clearly shown in Figure 3. Hingedly mounted as at 11 at the upper side and at the rear end of the tubular body portion 10, is a cover or lid 12 acting to close the rear end of the tubular body. Hingedly connected to the lower portion of the lid 12 is a latch 13 for engaging a lug 14 carried by the body portion 10 for retaining the lid in a closed position over the rear end of the tubular body. Hingedly connected at the upper portion and at the forward end of the body portion 10 as at 15, is a suitable ring 16 for mounting of a suitable lens 17 which forms a closure for the forward end of the tubular body portion. Hingedly connected to the lower side of the body portion is a suitable latch 18 for engaging a lug 19 projecting from the ring 15 whereby the ring and lens will be held in a closed position over the forward end of the tubular body.

As will be observed in Figure 3, the lid 12 and ring 15 fit over the ends of the tubular body portion and thus serve to exclude dust and moisture from the housing.

Mounted within the tubular body portion 10 and arranged adjacent the forward end of the tubular body is a disc of insulating material 20 which may be secured in position as by

means of L-shaped mounting brackets 21 secured to the tubular body as by means of bolts or other suitable fastening elements 22. This partition forming disc 20 is of a diameter equal to the internal diameter of the tubular body portion and divides the body portion into a rear or cell compartment 23 and a shallow front or lamp compartment 24. Arranged at the axial center of the insulating disc 20 and arranged respectively at the front and rear sides of the disc is a pair of metallic contact discs 25 and 26 each of which is provided with a pair of diametrically arranged tongues 27 which are intended to extend thru the insulating disc and be clamped about the peripheral edge of the companion contact disc as clearly shown in Figures 2 and 4 so that the tongues aside from providing a mounting means for the contact disc also form electrical connections between the front and rear discs. The front contact disc 25 is formed with a projection as shown in Figure 7 which is bent backwardly in spaced relation over the face of the disc proper to provide a yieldable contact finger 28. Aside from the provision of the contact finger 28 on the front contact disc 25, the discs 25 and 26 are of identical outline and it is preferred that the contact member 25 be formed of a resilient material to form a yieldable finger 28. Arranged concentric to and spaced from the contact discs 25 and 26, and arranged respectively at the front and rear sides of the insulating disc 20, is a pair of contact rings 30 and 32 which may be formed from sheet metal such as brass or copper. These contact rings 30 and 32 are also provided with bendable tongues 33 which project thru the insulating disc and are clamped about the peripheral edges of the companion ring for securing the rings in position at the front and rear sides of the insulating disc and also forming an electrical connection between the contact rings. Projecting forwardly from the upper portion of the front contact ring 30 and offset to one side of the vertical center of the tubular body portion 10 is an arcuate-shaped contact plate 34 which preferably forms an integral part of the contact ring.

The rear or larger compartment 23 is intended to receive a standard lantern battery 35 as shown in dotted lines in Figure 4, and which batteries are provided with the terminals 36 and 37 also shown in dotted lines in Figure 4. When the battery is positioned in the compartment 23, the terminal 36 will engage the rear contact disc 26 and the terminal 37 will engage the rear contact ring 32 and it will be observed that these contacts will be made regardless as to the position of the battery within the compartment. The rear wall of the cover or lid 12 is provided at its inner side with a suitable spring 12' which yieldably engages the rear end of the battery for normally urging the battery terminals 36 and

37 into electrical contact with the contacts 26 and 32 respectively.

Slidably and removably fitting in the forward end of the tubular body portion 10 is a reflector 38 having a flange 39 for attachment internally of the tubular body portion as by means of bolts or other fastening elements 40. The axial center of the reflector is shaped to provide a socket portion 41 which projects rearwardly and is internally threaded for receiving the threaded base of an electric lamp 42 of the single contact type. With lamps of the single contact type, the metal shell of the base serves as one terminal for the lamp while the second conductor for the lamp is in the form of a projection extending from the end of the lamp base. The reflector 38 is formed of metal and thus has electrical connection with the shell portion of the lamp base. When the lamp is threaded into the socket 41 the central contact engages the yieldable contact finger 28.

Referring now to the circuit controlling means for completing an electric circuit to the lamp 42, the same embodies a switch arm 44 of substantially T-shape in formation providing a cross head 45 and a stem portion 46. The lower end of the stem portion 46 is hingedly connected to a bracket 47 carried by the rear side of the metal reflector 38 above the socket 41. As will be observed, the switch arm 44 is arranged so that the cross head 45 has movement toward and away from the forward edge of the arcuate contact plate 34 and that the upper end of the cross head projects above the contact plate for engagement by a section of the switch operating means generally designated by the numeral 48.

The switch operating means is of the sliding type and embodies a slide strip 50 which extends longitudinally at the inner side of the tubular body portion 10 and has its forward portion slidably extending thru an opening 50' provided in the peripheral portion of the insulating disc 20. The forward end of the slide strip 50 which projects into the forward compartment 24 is provided with an inwardly offset bifurcated head 51 forming a pair of spaced arms between which the cross head 45 of the switch arm extends whereby upon longitudinal movement of the slide strip the switch arm will be moved forward and rearward in the casing about its pivotal connection with the bracket 47.

Arranged at the outer side of the body portion 10 is a longitudinally movable thumb piece 52 which is connected with the slide strip 50 by means of suitable fastening elements 53 the shank portions of which have sliding movement in guide slots 54. By observing Figure 5 it will be seen that the slide strip 50 has sliding movement along the inner surface of the tubular body portion 10 and that sliding movement of the thumb piece 52

5 imparts longitudinal sliding movement to the slide strip. By observing Figure 3 it will be seen that when the switch operating means is in its forward position that the switch arm 44 is out of engagement with the arcuate contact plate 34 and that when the operating means is moved rearwardly that the switch arm will be drawn into engagement with the contact plate for completing a circuit to the lamp 42. It may here be noted that by so forming the reflector 38 of metal that the tubular body portion 10 need not necessarily be made of metal since the housing forms no part of the electrical 10 connection between the battery and lamp. It will also be noted that when the switch arm 44 is out of engagement with the contact plate 34 that no electrical connection is made between the contact rings 30 and 32 and the 15 casing and thus there is little likelihood of the battery becoming short circuited.

20 Referring now to the supporting frame or stand B for horizontal mounting of the cylindrical housing A, the same embodies a 25 yoke 60 comprising a pair of upwardly converging side arms 61 which extend above and below the casing A and are connected at their upper ends by a head piece 62 which extends transversely of and in spaced relation above the cylindrical casing. The lower ends of the arms 61 are connected to a base ring 63. The cylindrical casing A is secured between the side arms 61 as by soldering, welding or the like at the point 64 with the 30 major portion of the casing projecting rearwardly of the yoke as clearly shown in Figure 1. Secured at their upper ends to the lower side of the cylindrical casing A and at the longitudinal center thereof, is a pair of 35 upwardly converging brace legs 65 having their lower ends secured to the base ring 63 at points substantially at a right angle to the points of attachment of the lower ends of the yoke arms 61. These legs 65 are secured 40 to the casing A at points forwardly and rearwardly of the yoke 60 and effectively brace the casing against tilting or rocking about its connections 64 with the yoke.

45 Connected at one end to the central portion 50 of the cross piece 62 and extending rearwardly therefrom with its rear end turned downwardly and secured to the rear end of the tubular body portion 10, is a hand grip 66 which may be grasped for handling the lantern so as to direct the light rays from the lamp 42 in any desired direction. Pivotedly 55 connected to the ends of the cross piece 62 is a bail handle 67 which may be employed for carrying the lantern or for hanging the lantern on a projection. As will be observed in Figure 1, the bail handle 67 may be swung downwardly over either end of the cylindrical casing into an out of the way position to allow ready grasping of the grip 66. A diagonal brace member 68 connects the central

portion of the head piece 62 with the forward end of the tubular body portion 10 for further rigid mounting of the housing in the supporting frame. By so having the major portion of the cylindrical casing project rearwardly 70 from the yoke 60, such permits of the hand grip 66 being of sufficient length to enable a person to readily place all of the fingers about the hand grip.

75 From the foregoing description it will be apparent that a novel and improved type of electric hand lantern has been provided embodying novel features of construction for rendering the lantern extremely rigid in construction and easily handled for different purposes, and one embodying a novel circuit controlling means whereby possibility of short circuiting is reduced to a minimum.

80 Changes in detail may be made to the form of invention herein shown and described, without departing from the spirit of the invention or the scope of the following claims.

85 I claim:

90 1. An electric hand lantern of the class described comprising a frame embodying a yoke portion including rigidly connected side arms and a head piece, a base ring connecting the lower ends of the side arms, a hollow cylindrical casing fixedly mounted horizontally between and with respect to the side arms and 95 projecting forwardly and rearwardly thereof, brace legs connecting the casing forwardly and rearwardly of the side arms with the base ring, illuminating means in the casing, a bail pivotally connected to the upper ends of 100 said side arms, and a hand grip connected to said head piece and the rear end portion of said casing.

105 2. An electric hand lantern comprising a supporting stand embodying side arms and a head piece connecting the upper ends of the arms, a hollow cylindrical casing fixedly mounted horizontally intermediate its ends between the side arms in spaced relation beneath the head piece, a bail handle connected with the upper ends of said arms, a hand grip connected at its forward end to the central portion of said head piece and projecting rearwardly therefrom with its rear end secured to the rear portion of said casing, and 110 illuminating means in the casing.

115 3. In an electric lantern, a tubular casing, a closure for the rear end of the casing, an insulating disc mounted intermediate the ends of the casing, contacts mounted in spaced relation on the disc and having portions arranged at each face of the disc, said contact portions at the rear of the disc to be engaged by the terminals of a storage cell positioned in the rear portion of the tubular casing, a 120 reflector mounted in the forward portion of the casing and having a socket portion, an electric lamp fitting in the socket portion in electrical contact therewith and having its opposite terminal engaging one of said contacts.

tacts, a switch arm pivotally supported on the reflector for engaging a companion contact and having electrical connection with the socket portion of the reflector, and operating means for imparting movement to the switch arm for completing a circuit between the storage cell and lamp.

4. In an electric lantern, a tubular casing, a closure for the rear end of the casing, a lens closing the forward end of the casing, an insulating disc mounted in the casing adjacent the forward end thereof, a pair of contacts mounted in spaced relation on the insulating disc and having portions arranged forwardly 10 and rearwardly of the disc, said contact portion at the rear of the disc to be engaged by the terminals of a storage cell insertable thru the rear end of the tubular casing, a metallic reflector mounted in the tubular casing forwardly of the insulating disc and having a 15 socket portion, a lamp fitting in the socket portion in electrical connection therewith and having its opposite terminal engaging one of said contacts, a switch arm pivotally and electrically connected to the rear side of the metallic reflector for movement into engagement with the companion contact, and operating means for the switch arm embodying a 20 slide strip detachably associated with the 25 switch arm.

5. In an electric lantern, a tubular casing for receiving a storage cell, an insulating disc mounted in the casing, inner and outer contacts mounted in spaced relation on the insulating disc and having portions arranged at 30 each face of the disc, said inner contact at the face side of the disc having a yieldable contact finger and said outer contact at the face side of the disc having a contact plate, 35 a metallic reflector mounted forwardly of the disc and having a socket portion, an electric lamp fitting in the socket portion in electrical connection therewith and having its opposite terminal engageable with said contact finger, 40 a switch arm pivotally and electrically connected to the reflector, and operating means for the switch arm for moving the same into engagement with said contact plate for completing a circuit between the storage cell and 45 lamp.

6. In an electric lantern, a tubular casing, an insulating disc mounted in the casing, contact discs arranged at each side of the insulating disc at the axial center thereof and each 55 having fingers extending thru the insulating disc for engagement with the companion contact disc, said contact disc at the face side of the insulating disc having a contact finger, a 60 pair of contact rings arranged one at each 65 face of the insulating disc and each having tongues extending thru the insulating disc for engagement with the companion contact ring, said contact ring at the face side of the insulating disc being provided with a contact 70 plate, a reflector mounted forwardly of the 75

insulating disc and having a metallic socket portion arranged forwardly of said contact finger, an electric lamp threaded in the socket portion with its central contact engaging the contact finger, a switch arm pivotally supported at the rear side of the reflector in electrical connection with said socket, and operating means for the switch arm embodying a slide strip having a bifurcated head providing spaced arms embracing opposite sides of the switch arm for swinging movement of the free end of the arm into and out of engagement with said contact plate.
